C. TAYLOR.

METHOD OF BLEACHING AND APPARATUS THEREFOR.

APPLICATION FILED SEPT. 20, 1920.

1,396,792.

Patented Nov. 15, 1921.

Inventor:

Charles Taylor.

per Ferdinand Broster Bonhardt

Attorney.

UNITED STATES PATENT OFFICE.

CHARLES TAYLOR, OF KEARSLEY, NEAR MANCHESTER, ENGLAND.

METHOD OF BLEACHING AND APPARATUS THEREFOR.

1,396,792.

Specification of Letters Patent.

Patented Nov. 15, 1921.

Application filed September 20, 1920. Serial No. 411,566.

To all whom it may concern:

Be it known that I, CHARLES TAYLOR, a subject of the King of Great Britain, residing at 123 Station road, Kearsley, near Manchester, in the county of Lancaster, England, have invented certain useful Improvements in Methods of Bleaching and Apparatus Therefor, as set forth in the annexed specification.

10 This invention relates to the bleaching of fabrics in piece form.

Hitherto it has been customary when employing round keirs for the bleaching process, to fill the boiling keir by hand, and after 15 the boil was complete, to remove the cloth from the boiling keir into the chemical and acid tank again by hand which method necessitated the employment of a number of skilled piling boys, a considerable loss of 20 time in filling the keirs, faulty bleaching, and repeated handling by the operatives of the whole of the pieces attached together.

The object of my invention is to render the process of bleaching automatic from beginning to end, whereby the amount of skilled labor and time employed is greatly reduced, chemicals are economically utilized, danger to life is reduced, and a comparatively perfect bleach is obtained.

30 According to my invention, my improved method consists in leading the pieces in rope form automatically from one keir direct into the next keir, and direct from the last keir through the white mangle into the folding device.

My improved plant for carrying out said method includes a round iron keir, a round wood keir, an expander, a white mangle and a folding device arranged in a row, in combination with an automatic piler arranged over each keir and rotated means for passing the fabric in rope form from one keir to the piler on the next keir used in performing the bleaching operation.

45 I attain the hereinbefore recited objects by the hereinafter described method and the plant illustrated diagrammatically in the drawing which I have caused to be appended hereunto.

50 Referring to the drawing which shows a plant for handling 10 tons per 12 hours, two iron keirs 1, 2 are arranged in alinement with a singeing machine or padding machine (not shown), a set of squeezing and drawing

rollers 3 being interposed between the first 55 keir 1 and the said machine. Two wood keirs 4, 5 are also provided in alinement with the iron keirs 1, 2 and a mangle 6 is interposed between the second iron keir 2 and the wood keir 4. Each of the keirs 1, 2, 4 and 5, 60 which as shown may be of the bottle neck type, has an automatic piler 7 suspended above it from a beam 8, said pilers 7 being preferably constructed and arranged to operate as described in Patent No. 1,328,615, issued on the 20th January, 1920, and a mechanically rotated guide drum 9 is mounted above each keir to pass the fabric direct from the squeezing and drawing rollers 3 into the upper end of the automatic piler 7 on one 70 or other of the iron keirs 1, 2 and direct from either of the iron keirs 1, 2 into the automatic piler 7 of one or the other of the wood keirs 4, 5. Situated in alinement with the wood keirs 4, 5 I provide a white mangle 10 and 75 two folding devices 11 and I mount on the beam 8, two expanders 12, the arrangement being such that the fabric can be passed direct from either of the wood keirs 4, 5 through one of the expanders 12 and from 80 thence through the white mangle 10 into one of the folding devices 11. In lieu of one white mangle for both cloth ropes, I may provide a separate white mangle for each of them.

85 The improved method of bleaching as performed on the improved plant illustrated consists in passing the end of two fabric ropes 13, 14 through the mangle 3 when it emerges from the singeing machine 90 or padding machine, and in passing the rope 13 into the automatic piler 7 on the iron keir 2 and the rope 14 into the iron keir 1, whereupon the pilers 7 automatically fill the keirs 1 and 2. After the boil 95 is complete, the accessible end of the rope 13 is lifted from the iron keir 2 and led to the automatic piler 7 on the wood keir 4, which is then filled by the piler 7, and the accessible end of the rope 14 is led to 100 the piler 7 of the wood keir 5 which is then filled by its piler 7. On completed bleach the accessible end of the pile ropes 13 and 14 are passed by the operative 105 through the expanders 12 of any known construction such as is usually employed for opening out the cloth from its rope form and spreading it to its full width and

through white mangle 10 to the folders 11 which then automatically empty the wood keirs 4, and 5.

It will be appreciated that during the whole duration of the bleaching process, only the extreme end of each rope of fabric requires to be manually handled and that such handling is only necessary for short periods with long intervals between. When employing my improved piler, the liquor is pumped into the keirs by the pumps 15 and by passing through the piler 7 with the fabric rope effects the introduction of the rope into the keirs. The chemicals, after use in the wood keirs 4 and 5 are returned to tanks 16 and 17 from whence they are again pumped back in to wood keirs during the next piling operation.

I claim:

20 1. A method of bleaching cloth in rope form in keirs, consisting in passing two ropes of cloth simultaneously through a mangle; mechanically introducing into and automatically piling in a boiling keir one 25 of said ropes; mechanically introducing into and automatically piling in a second boiling keir, the other of said ropes in a simultaneous manner; boiling said ropes of cloth; withdrawing said ropes and passing 30 them simultaneously through a mangle; mechanically introducing into and automatically piling in a wood keir one of said ropes; simultaneously introducing mechanically into and automatically piling in another wood keir the other of said ropes; treating said ropes in said wood keirs; 35 simultaneously withdrawing and expanding said ropes; passing said ropes together

through a white mangle; and then simultaneously folding both of said ropes of 40 cloth.

2. An improved bleaching plant comprising a round iron keir, a round wood keir, an expander, a white mangle and a folding device arranged in a row, in combination with an automatic piler arranged over each keir and rotated means over each keir adapted to pass the fabric in rope form from one keir to the piler on the next keir used in performing the bleaching operation. 45 50

3. An improved bleaching plant comprising in combination, a set of squeezing rollers; two iron keirs in alinement with said set of squeezing rollers; two wood keirs in alinement with said iron keirs, a second set 55 of squeezing rollers interposed between said iron keirs and wood keirs; two folding devices in alinement with said wood keirs; a white mangle between said folding devices and said wood keirs; an automatic 60 piler arranged over each of said keirs; a member supporting said pilers; rotated drums mounted on said member to guide cloth in rope form to said pilers; and expanders on said member to expand the 65 cloth in rope form before it passes through the white mangle, for the hereinbefore specified purpose.

Signed at Manchester, in the county of Lancaster, England, this 9th day of September, 1920.

CHARLES TAYLOR.
